US0D1079854S

(12) **United States Design Patent** (10) **Patent No.:** **US D1,079,854 S**
(45) **Date of Patent:** **** Jun. 17, 2025**

(54) **HAND GRIP STRENGTHENER**

(71) Applicant: **MACBO TECHNOLOGIES LLC**,
Denver, CO (US)

(72) Inventor: **Yiming Gao**, Shenzhen (CN)

(73) Assignee: **MACBO TECHNOLOGIES LLC**,
Denver, CO (US)

(**) Term: **15 Years**

(21) Appl. No.: **29/987,513**

(22) Filed: **Jan. 24, 2025**

(30) **Foreign Application Priority Data**

Oct. 1, 2024 (CN) 202430629072.7

(51) **LOC (15) Cl.** **21-02**

(52) **U.S. Cl.**

(57) **CLAIM**

The ornamental design for a hand grip strengthener as shown and described.

DESCRIPTION

FIG. 1 is a front, left, top perspective view of a hand grip strengthener showing my new design;

FIG. 2 is front, left, bottom perspective view thereof;

FIG. 3 is front, right, top perspective view thereof;

FIG. 4 is a front elevation view thereof;

FIG. 5 is a rear elevation view thereof;

FIG. 6 is a left-side elevation view thereof;

FIG. 7 is a right-side elevation view thereof;

FIG. 8 is a top plan view thereof; and,

FIG. 9 is a bottom plan view thereof.

The broken lines depict portions of the hand grip strengthener that form no part of the claimed design

1 Claim, 9 Drawing Sheets
